UNITED STATES PATENT OFFICE.

HARRY H. HARRIS, OF OCONTO, WISCONSIN, ASSIGNOR OF FORTY-FIVE PER CENT TO
FRANK McDOWELL, OF OCONTO, WISCONSIN.

JAR COVER.

Application filed September 30, 1925. Serial No. 59,614.

This invention relates to jar covers, and the object of the invention is the construction of a simple and efficient jar cover, including a separable or split cap band, and a 5 pin, both of a peculiar novel structure for holding the completed cover upon a jar or receptacle when assembled and in position thereon.

With the foregoing and other objects in 10 view, my invention comprises certain novel constructions, combinations, and arrangements of parts as will be hereinafter fully described, illustrated in the accompanying drawings, and more particularly pointed out 15 in the appended claims.

In the drawings:

Figure 1 is a view in side elevation of a jar and my improved cover thereon.

Figure 2 is a top plan view of the structure shown in Figure 1.

Figure 3 is a sectional view taken on line 3—3, Figure 2, and looking in the direction of the arrows.

Figure 4 is a fragmentary view, in elevation, of the cap band and pin; the cap band being in a separated position at its split ends.

Figure 5 is a view in elevation showing jars equipped with my jar cover in a tiered or stacked condition.

Referring to the drawings by numerals, 1 is the glass jar upon which is positioned a 25 my improved jar cover. This cover includes a springy cap band 2; band 2 is split and is provided with preferably a pair of sleeve-like 30 vertical ears 3 and a single sleeve-like vertical ear 4, Figure 4. The single ear 4 fits in between ears 3 and these ears are apertured for receiving the straight vertical portion 5 of the springy or resilient pin 6. This 35 pin 6 is bowed at 7, and is provided with an inwardly extending bowed tongue 8, for the purpose hereinafter described. When the 40 pin 6 is in the ears 3 and 4, the cap band 2 will be securely held on the jar 1.

The cap band 2 is provided with an up- 45 standing bead 9 that is cut away at 10, at the split ends of the band 2, producing a socket in which the bowed portion 7 of the pin is seated, so as to place the pin 6 out of 50 the way when the jars are tiered or stacked, as clearly shown in Figure 7. In packing the jars away in a shipping crate or on a shelf, as in a delicatessen store, it is often desirable to stack the jars for economizing

space, and my invention is excellent for this 55 purpose.

In assembling the jar cover, I preferably place a rubber band 11 on the top edge of the jar, Figure 3, and then on this rubber band, I lay a glass top 12 upon which I place the 60 peculiarly constructed cap band 2, closing the same together so that the ears 3 and 4 register, and then I insert the pin 6 and swing the pin so that the tongue 8 "snaps" 65 down over the bead 9, resting upon the top 12, as clearly seen in Figure 3, with the pin out of the way in a socket formed by ends 10, as shown in Figure 1. When it is desired to remove the jar cover, the operator grasps the tongue 8, Figure 3, swings the tongue around 70 to the dotted position A, Figure 3, then pulls upwardly on the pin, until it is removed from the ears, whereupon the cap band spreads apart, allowing its removal from the jar and then the top 12 and rubber 75 band 11 can be removed, either by the use of the fingers only, or with a knife.

If desired, without departing from the spirit or scope of this invention, the cover 12 may be a paraffin treated piece of card- 80 board, and if so, the use of the rubber band 11 will be unnecessary.

As shown in Figure 5, the jars 1 can be stacked for saving space.

It will be understood that my cover can 85 be taken off easily after being sealed tight. It will also be understood that my improved jar covers can be used on jars, bottles, or buckets, or on any article where a cover is necessary. The threaded cap band is made 90 of strips, therefore, is a saving of material, and it can either be rolled or pressed out. The ears of the band are preferably shaped from one piece of material and can be welded or made firm in any way to suit the 95 constructor.

It is to be noted that in Figure 3, the top 12 is made of clear glass, so that if the contents of the receptacle starts to spoil, this condition can be seen through the top, 100 and by recooking or reboiling the contents, it may be saved; the housewife is, therefore, enabled to keep herself informed as to the condition of her "canned" goods.

It is to be understood that with my flat 105 or smooth tops or covers, after the band has been removed, a knife can be passed freely under the same and over the top of the jar

or receptacle to loosen the top, without striking ridges or grooves, as in other caps or jars, making it easy to remove the cap in a way without liability of breaking the cap or top of the receptacle.

While I have described the preferred embodiment of my invention and illustrated the same in the accompanying drawings, certain minor changes or alterations may appear to one skilled in the art to which this invention relates, during the extensive manufacture of the same, and I, therefore reserve the right to make such changes or alterations as shall fairly fall within the scope of the appended claims.

What I claim is:

1. In a device of the class described, the combination with a top, of a split cap band provided on its upper edge with an upwardly standing bead, said bead being cut away at its ends, producing a socket on the band, said band provided with registering ears at its ends, a pin extending into said registering ears for holding the ends of the band together, said pin provided with an upwardly bowed portion and with an inwardly-extending resilient tongue, and said upwardly bowed portion seated in said

socket between the ends of said bead with the tongue resting down on said top out of the way, whereby a jar or receptacle may be stacked or tiered upon said top, substantially as shown and described.

2. In a device of the class described, the combination with a top, of a split band clamped around said top, said band provided with registering ears and with a socket, and a pin in said ears and having a portion extending through the socket, said extending portion terminating in a tongue normally resting tight upon said top.

3. A jar cover, comprising a split band, said band provided on its split ends with sleeve-like vertical registering ears, and a vertically-movable locking pin in said ears.

4. A jar cover, comprising a split band, said band provided on one of its ends with a pair of sleeve-like vertical ears, and on its other end with a single sleeve-like vertical ear between the ears of said pair, and a vertically-movable locking pin in all of said ears.

In testimony whereof I hereunto affix my signature.

HARRY H. HARRIS.
